Specification for Design.

Patented Dec. 10, 1912.

Application filed June 28, 1912. Serial No. 706,539. Term of patent 7 years.

To all whom it may concern:

Be it known that I, EDWARD L. ANDERSON, a citizen of the United States, and residing in Attleboro, in the county of Bristol and Commonwealth of Massachusetts, have invented a new, original, and ornamental Design for a Collar-Fastener, which is illustrated in the accompanying drawing, forming part of this specification.

Figures 1 and 2, respectively, are obverse and reverse views of the collar fastener and Fig. 3 is an edge view of the same.

I claim—

The ornamental design for a collar fastener as shown.

In testimony whereof I have signed my name in the presence of two witnesses.

EDWARD L. ANDERSON.
